SAFETY WINDOW

Filed June 14, 1929

*Inventor:
Frank S. O.,
By W. Bartlett Jones, Atty*

UNITED STATES PATENT OFFICE

FRANK SOO, OF CHICAGO, ILLINOIS

SAFETY WINDOW

Application filed June 14, 1929. Serial No. 370,783.

The present invention relates to safety windows and has special reference to a construction of the window and the gate therefore.

5 It is a custom to provide window gates which open and close with motion of the window. If the gate is provided with a fastener by which it may be detached from the movable sash, there is danger of the gate 10 being left detached and hence of the window being left unprotected if open. If the gate is more permanently attached, considerable difficulty or inconvenience may be experienced in washing the window or in removing the 15 gate to wash the window.

The present invention provides a window gate of novel construction which may be permanently associated with a window sash in which the window glass is mounted in a movable frame.

20 One object of the invention is to provide window sashes with a movably mounted glass therein, such as a door-like mounting.

Another object of the invention is the provision of a novel gate that is compact in folded form and suitable for permanent association with the sash.

25 Still another object of the invention is the provision of a casing to house the folded gate.

Various other objects and advantages of the invention will become apparent from the following description of the invention as it is illustrated by the several embodiments 30 shown in the accompanying drawings, in which

Fig. 1 shows a window open to expand a gate.

Fig. 2 is a side view of the window of Fig. 40 1 on line 2-2 of Fig. 1.

Fig. 3 is a view of the window with the gate closed.

Fig. 4 is a side view of a regular length window showing the gate mounted in the outside runner, and protecting casing.

Fig. 5 is a detail view of the gate construction.

Fig. 6 is a cross-section of the sliding joint on line 6-6 of Fig. 1.

It is of course to be understood that the 50 invention is not to be considered as limited to or by the disclosures shown in the drawing, as will appear more fully hereinafter. The invention is susceptible to change and modification to include other embodiments 55 which may fall within the spirit and scope of the appended claims.

In the drawings a window casing 10 is illustrated in which upper sash 11 slides between runners 12 and 13 and lower sash 14 60 slides between runner 13 and 15.

Each sash carries a frame 16 in which a glass 17 is mounted. The frame is suitably removable from the sash being shown hinged thereto in door-like fashion by hinges 18 and 65 19, so arranged that the glazed frame swings into the room. A lock or fastener 20 is indicated for the glass carrying frame.

The lower sash is shown in Figs. 1 and 2 to be shorter than is customary, to provide an 70 extra space at the bottom for mounting a closed window gate. The gate is one which may be compactly and tightly closed.

A casing or angle plate 21 may be employed 75 in front of the closed gate, and it is shown mounted within runner space so that its top 22 provides a stop for the lower sash 14.

The gate which is employed comprises a plurality of parallel bars connected by expandable mechanism, preferably of the toggle-like structure, which do not prevent close fitting of the bars in the folded form of the gate. In this present instance each bar 23 is a slotted hollow bar which comprises two channel strips 24 and 25 (Fig. 6) spaced 80 apart with the channel openings facing each other. The channels are rigidly secured in this position relative to each other by pivots 26 and spacers 27. In addition, the end bars, as shown in Fig. 5 may have other spacers, 85 90

such as the pins 28 and block 29, upon which pins 28 brackets 30 are mounted which are screwed to the window sash 14 by screws 31.

Each intermediate bar at pivot 26 has two links fitting within space 32 (Fig. 6) between the channels, each being directed toward the adjacent bar at which each terminates. Taking one pivot 26, for example, there are links 33 and 34, one going to each adjacent bar. 5 Where the various links 33 and 34 cross there is a pivot 35 connecting them. The free ends of links 33 and 34 are mounted on a common pivot 36 which is mounted slidably within the two channels. Running blocks 37 10 and 38 are indicated also mounted on the pivot 36 for guiding the pivot in the channels.

Each side of the gate has the same structure and the links are sufficiently short so that in folded form of the gate the free 20 ends on pivots 36 do not move beyond the center of the bar. Thus the gate may be folded and the links housed completely in the channel space, as shown in Fig. 3.

In Fig. 4 a modification is shown in which 25 a regular length of lower sash 40 is employed, the gate being secured by its lower bar 41 to the ledge 42 by screws 43. The upper bar 44 is secured by bolts 45 to a housing or casing 46 which is carried by the lower sash 40.

30 What I claim is:

1. A window gate comprising a plurality of parallel hollow slotted bars, a pair of pivotally crossed links between the ends of each pair of adjacent bars, each link being pivoted 35 at one end to one bar, and being mounted to an adjacent bar slidably lengthwise and internally of the bar.

2. A window gate comprising a plurality of parallel hollow slotted bars, a pair of pivotally crossed links between adjacent bars, each link being pivoted at one end to one bar 40 internally of the bar, and being mounted to an adjacent bar slidably lengthwise and internally of the bar.

45 3. In a window gate a pair of adjacent parallel bars each bar comprising two spaced channel members rigidly mounted together with the channels face to face, links pivotally mounted at one end to one bar within the 50 space between the channel members, and slidably mounted at the other end within the channel of the other bar, and guiding means pivoted to the link running in one of said channels.

55 4. A safety window comprising in combination, a window frame, upper and lower 60 slidable sashes, the lower sash being short to provide an opening between the window ledge and the lower sash in the closed condition of the sashes, and an expansible window gate secured to the ledge and to the lower sash, said gate in closed form filling and sealing the open space below said sash, and comprising parallel hollow slotted bars and link

means between them mounted internally of the bars.

5. In a window gate a pair of adjacent parallel bars each bar comprising two spaced channel members rigidly associated together 70 with the channels face to face, and links pivotally mounted at one end to one bar within the space between the channel members, and slidably mounted elsewhere along its length 75 in the space between the channels of the bar.

In witness whereof, I have hereunto affixed my signature.

FRANK SOO.
